UNITED STATES PATENT OFFICE.

RICHEY L. SWARTZ, OF BOWLING GREEN, OHIO.

WASHING MACHINE.

Application filed June 4, 1921. Serial No. 474,910.

To all whom it may concern:

Be it known that I, RICHEY L. SWARTZ, a citizen of the United States, and a resident of Bowling Green, in the county of Wood and State of Ohio, have made an Invention Appertaining to Washing Machines; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to washing machines, and particularly to those of the swinging tub type as distinguished from washing machines of the rotary tub and oscillating dolly types.

The primary object of the invention is the provision of a washing machine having a clothes container or basket mounted for rocking movements within the tub thereof and having mechanism operable to impart predetermined opposed rocking movements to the tub and container, whereby the washing liquid within the tub is forced with greater velocity and cleaning effect through the container and clothes therein than would be the case if either the tub or container alone were rocked.

Further objects and advantages of the invention will be apparent from the following detailed description thereof.

While the invention, in its broader aspect, is capable of embodiment in numerous forms, a preferred embodiment thereof is illustrated in the accompanying drawings, in which,—

Figure 1 is an end elevation of a machine embodying the invention, with parts broken away. Fig. 2 is a fragmentary detail of one of the basket carrying arms and its supporting member taken on the line 2—2 in Fig. 1. Fig. 3 is a side elevation of the machine, with parts broken away, and Fig. 4 is a diagrammatical view illustrating the relative movements of the tub and basket.

Referring to the drawings, 1 designates a frame of rectangular skeleton form having a beam member 2 mounted on the top thereof along each of its front and rear edges. The frame also has a stationary upright member 3 at each side thereof centrally of its ends.

The tub 4 of the machine is suspended for rocking movements lengthwise of the frame by two sets of rocker-arms 5, which are pivotally suspended from bearings 6 secured to the ends of the respective members 2 and 60 resting on the top side bars of the frame. The lower end of each rocker-arm 5 has a pin or stud 7 projecting inward therefrom under a respective hooked bearing lug 8 on the adjacent tub end. It is evident that the 65 ends of the tub project freely between the suspending arms of the respective pairs and that the tub is suspended by the arms in a manner to permit free horizontal swinging movements of the tub lengthwise of the 70 frame. The ends of the tub are vertically rounded in convex form with respect to the tub center and the tub is provided with a large opening in its top but which is restricted with respect to the ends of the tub. 75 The tub may be lowered from the rocker-arms and removed from the frame by merely swinging the rocker-arms and their studs 7 out from engagement with the hooks 8.

The clothes container or basket 9 is provided with impervious sheet metal sides and has its bottom and ends formed of any suitable pervious material, such, for instance, as wire mesh, to permit a free circulation of 85 the washing liquid therethrough. The container is open at its top, in the present instance, between the two top cross-bars 10, which connect the sides and act as bracing means therefor. While the container may 90 be of various shapes it is preferable to vertically round the ends thereof and to have the bottom drawn upward at its center to form a transverse inverted V-shaped ridge within the basket. A cross reinforcing bar 11 is 95 provided at the apex portion of the bottom. The container 9 is pivotally suspended for vertical rocking movements by a pair of arms 12, which are rigid with respect to the frame and project down into the tub 4 near 100 opposite sides thereof from the respective members 2 to which the arms are rigidly secured, as best shown in Fig. 2. The lower ends of the arms 12 are provided with bayonet slots 13 for releasably receiving bearing 105 studs 14 projecting from the respective sides of the container 9, such studs being located at approximately the center of the container sides.

An upright lever 15 is disposed at the 110

inner side of each upright frame bar 3, being pivoted thereto at 16, which pivot, in the present instance, is located below the rocking pivot of the container 9. The upper end of the lever 15 extends above the frame and is provided with a handle 17 to facilitate a hand rocking of either lever. The handle 17 in the present instance is carried by an inverted U-shaped member 18 which has one leg provided with a vertical slot 19 for pivotally and adjustably straddling a pivot stud 20 on the respective lever, and has its other end extending down within the tub 4 at the respective outer side of the container 9 and fixedly connected to the container side at a point above its rocking pivot 14, as at 21. It is thus evident that upon a rocking of the lever 15, which really includes as a part thereof the member 18, the container will be caused to rock on its rocking axis.

In order that a rocking of the levers 15 may also impart swinging movements to the tub 4 the tub suspending arms 5 of one pair 25 are connected to the respective levers 15 by links 22, which are in pivotal connection at their ends with the arms and lever connected thereby. It is clear by reference to Fig. 4 that when the upper ends of the levers 15 are rocked to the left from the full line position the tub will be swung to the left to the dotted line position, and that the container 9 will at the same time be rocked upward at the right from the heavy dotted line position to the light dotted line position, thus causing opposed movements of the tub and basket, which is evidenced by the fact that the right hand end of the container during such movement swings up toward the approaching right-hand end of the tub. This action causes a restriction of the spaces between the tub and container at first one end and then the other thereof as the rocking continues and a consequent forcing of the water by the tub ends, first in one direction and then another through the container lengthwise thereof, the force of movement of the water being considerably greater than would be the case if either the tub or container alone had movement.

To provide a power operating means for the levers 15 a motor 23 is mounted on the bottom portion of the frame at one end thereof and connected by a belt 24 to a pulley 25 mounted, in the present instance, on a shaft 26 with a fly wheel 27. This shaft is journaled in a bearing 28 and has a worm 29 in mesh with a worm-wheel 30 on a shaft 31 journaled in the bearing 28 and extending crosswise of the frame. This shaft carries a clutch controlled crank-wheel 32, the crank-pin 33 of which is connected by a pitman 34 to a cross rod 35 connecting the lower ends of the two levers 15 at a point 60 below the tub. It is thus evident that a

turning of the crank-wheel 32 will impart predetermined rocking movements to the levers.

I wish it understood that my invention is not limited to any specific construction, arrangement or form of the parts, as it is capable of numerous modifications and changes without departing from the spirit of the claims.

Having thus described my invention, what I claim as new and desire to secure by Letters Patent, is,—

1. In a washing machine, a frame, a tub carried for horizontal swinging movements by the frame, a perforated clothes container carried by the frame within the tub for rocking movements relative to the frame and tub, and mechanism connected both to the tub and to the container and operable to simultaneously impart swinging movements to the tub and rocking movements to the container.

2. In a washing machine, a frame, a tub carried for horizontal swinging movements by the frame, a perforated clothes container carried by the frame within the tub for vertical rocking movements relative to the frame and tub, and means connected to both the tub and container and operable to impart simultaneous swinging movements to the tub and rocking movements to the container with the movements of the tub and container in different directions.

3. In a washing machine, a frame, a tub carried for swinging movements by the frame, a perforated clothes container carried by the frame within the tub for rocking movements relative to the frame and tub, an operating member pivotally carried by the frame at a side of the tub and having connection with the tub whereby a rocking of the member imparts swinging movements to the tub and having connection with the container whereby a rocking of the member causes a rocking of the container.

4. In a washing machine, a frame, a tub carried by the frame for swinging movements in a vertical plane, a perforated clothes container carried by the frame within the tub for rocking movements in a vertical plane relative to both the tub and frame, a vertically disposed lever pivoted for rocking movements to the frame with its pivot vertically offset from the rocking axis of the container, connection between the lever and tub to impart swinging movements from one to the other, and connection between the lever and container to impart rocking movements from one to the other.

5. In a washing machine, a frame, swinging arms suspended within the frame, a tub removably carried by the arms for swinging movements therewith, arms rigidly carried by the frame and extending down into the tub at the sides thereof, a perforated clothes

container pivotally carried by the last mentioned arms for rocking movements relative thereto, and means connected to both the tub and the container and operable to impart simultaneous swinging movements to the tub and rocking movements to the container.

6. In a washing machine, a frame, a tub suspended within the frame for swinging movements in a vertical plane, a perforated cloths container suspended from the frame within the tub for rocking movements relative to the frame and tub, a vertically dis-

posed lever pivoted to the frame at a side of the tub with its pivot vertically offset 15 from the rocking axis of the container, a member connecting the upper end of the lever to the container to impart rocking movements to the container when the lever is rocked, and connection between the lever 20 and tub to impart swinging movements to the tub from rocking movements of the lever.

In testimony whereof, I have hereunto signed my name to this specification.

RICHEY L. SWARTZ.
